UNITED STATES PATENT OFFICE

ARGYLE CAMPBELL, OF CHICAGO, ILLINOIS, ASSIGNOR TO ENTERPRISE RAILWAY EQUIPMENT COMPANY, OF CHICAGO, ILLINOIS, A CORPORATION OF ILLINOIS

RAILWAY DUMP CAR CONSTRUCTION

Application filed January 21, 1931. Serial No. 510,090.

My invention relates to railway dump car construction, and more particularly to the construction of dumping door bracing and door operating means cooperating therewith.

5 It is a particular object of my invention to provide improved door bracing and supporting means for a dumping door whereby the number of parts will be reduced and greater rigidity obtained.

10 Another object of my invention is the provision of an improved door beam member such as will provide for economical distribution of metal.

Still another object of my invention is to 15 provide a cast metal beam member which will incorporate in one piece bracket means for accommodating removable load diverting means for the purpose of enabling the economical adaptation of the car to ballast-20 ing service.

Another object of my invention is to provide improved shaft rotating means for receiving a removable operating bar to provide safety and convenience to the operator in 25 the manipulation of the car doors.

My invention resides in certain features of construction and details of parts such as will hereinafter be more fully pointed out and claimed.

30 For further comprehension of my invention reference may be had to the accompanying drawings, wherein

Fig. 1 is a vertical transverse sectional view of the lower portion of a so-called W-type hopper showing so much of the car as necessary to illustrate my improvements incorporated therein;

Fig. 2 is a side elevation of that portion of the car illustrated in Fig. 1 and as viewed 40 on a line 2-2 of said Fig. 1;

Fig. 3 is a vertical longitudinal sectional view taken through the car on a line 3-3 of Fig. 1, certain of the parts being cut away adjacent the longitudinal center of the car to 45 better illustrate the construction of the mechanism and bracing;

Fig. 4 is a detached view on an enlarged scale of the improved door brace as viewed on a line 4-4 of Fig. 3;

50 Fig. 5 is a perspective view of the shaft

rotating member as viewed from the outside of the car;

Fig. 6 is a vertical side elevational view on an enlarged scale of the shaft rotating member;

Fig. 7 is a plan view of the shaft rotating member as viewed in Fig. 6;

Fig. 8 is a vertical transverse sectional view of the lower part of that portion of the car shown in Fig. 1, modified to show the 60 application of a ballast diverting attachment located over each of the rails;

Fig. 9 is a vertical side elevational view of that portion of the car shown in Fig. 8, with the doors in closed position;

Fig. 10 is a view similar to Fig. 9 except that the door is shown in open position;

Fig. 11 is a vertical transverse sectional view of a car similar to Fig. 1, illustrating a modified form of bracing wherein a beam 70 composed of a commercial channel bar section is utilized; and

Fig. 12 is a vertical longitudinal sectional view through that portion of the car illustrated in Fig. 11 as taken on line 12-12 of 75 Fig. 11.

Referring more particularly to the construction illustrated in Figs. 1 to 7, inclusive, the car broadly includes a centersill structure A, side walls B-B, and discharge hoppers on each side of the centersill structure, each of said hoppers being defined by inner and outer walls C and D, respectively, and transversely extending walls E and F, respectively, said walls being inclined lengthwise of the car. Each hopper is provided with a discharge opening adapted to be closed by a dumping door G. The doors on the respective hoppers are disposed in transversely aligned relation, and united at their 80 free edges by a beam member H which extends across the plane of the centersill. Each door is pivotally mounted on pivots J adjacent its upper margin on a combined brace and hinge member K. Intermediate 85 the pair of spaced doors and cooperating with the door beam H, there is disposed door operating and locking means L which is operated by means of a shaft M, the latter having shaft rotating and locking means N

identified therewith and disposed adjacent the car side.

Inasmuch as each door of the pair is of similar formation, the description herein-after following will be confined to one door. Each door G is formed of metal presenting a substantially flat and smooth main body portion 10, said door being rigidified adjacent its marginal edges as indicated at 11, 12, 13 and 14, respectively. The door on its underside is provided with the usual hinge straps 15—15 each cooperating with hinge lugs 16—16 formed integrally with the hinge member K, said lugs being adapted to receive the door pivots J.

The door G extends slightly beyond the inner face of the hopper bottom and side walls for the purpose of providing a bearing between the door surfaces and hopper walls, 20 the inner hopper side wall C being deflect- ed inwardly as at 7 thence outwardly to provide a shoulder 18 in engagement with the floor surface of the door. The outer hopper floor sheet D is reinforced on its 25 outer surface with an overlying rigidifying member 19 of appreciable width and flanged outwardly at 20 and 21, respectively, to present a channel shaped section. The flange 21 is further flanged at substantially right angles to the door surface as indicated at 22, and the flanges 21 and 22 cooperate with the door to form a tight joint at the outer side of the door. The member 19 adjacent the upper portion of the hopper overlies and 30 is riveted to a flange 23, the latter being formed integrally with the combined hinge and brace member K. At its lower edge the member 19 is flanged beneath the bottom hopper floor sheet as indicated at 24, and 35 overlying the said flange 24 is the reinforcing angle member 25 which extends from side to side of the car and ties together the pair of transversely aligned hopper sections.

The beam or bottom member H which connects the respective doors G—G of the pair preferably consists of a cast metal integral member formed with a flange presenting on opposite sides thereof attaching flanges 26 and 27 whereby the member is riveted to the under side of the door. Adjacent the inner edges of the doors the member is depressed as indicated at 29 to provide an offset construction with respect to the edge flanges 12 of the doors. Outstanding from said flanges 26 and 27 the beam is provided with a web-like body portion 30 which is deflected from a normal or right angular position with respect to the main body portion of the door for the purpose as will be hereinafter described. The outer portion of the web 30 is provided with a reinforcing marginal flange 31 of bulb-like formation. The beam H intermediate the doors is of appreciable depth and gradually reduces in depth 50 towards its outer ends, thereby providing a

fishbelly formation. Intermediate the pair of doors the body portion 30 is formed with an enlarged portion 32 having an elongated circular opening 33 formed therein which extends substantially in the direction of the 70 web and is formed intermediate its end with a non-circular recess 34 for the purpose of accommodating a nut 35. The opening 33 is adapted to receive the threaded shank 36 of a door operating mechanism eyebolt 37. 75 The recess 34 provides a snug fit for the nut 35 and maintains the same against both lengthwise and turning movement.

Connecting with the eyebolt 37 is the door operating mechanism L which includes an 80 arm 38 rigidly mounted upon the shaft M, said arm being in turn pivotally united as at 39 with a rigid link member 40. The opposite end of said link is pivotally united with the eyebolt as at 41. The shaft M is 85 supported in bearings in the bearing brackets 42 and 43 at the centersills and adjacent the side of the car, respectively. The rigid link member 40 is bent slightly as at 44, Fig. 3, in order that when the doors are in closed position the line of force extending through the respective pivotal connections 39 and 41 at the opposite ends of the link will pass slightly beyond the axial center of the shaft, thereby providing a jackknife dead center locked 90 connection between the door and the shaft.

The fact that the body portion 30 of the beam H and the eyebolt shaft 36 are disposed at an angle to the normal relatively to the plane of the main body of the door provides for a substantially straight line pull on the eyebolt member when the door is in closed position and insures against breakage of parts. The shaft rotating means N includes a toothed element 45 rigidly united with the 100 shaft M, and cooperating with said member 45 is a pivotally mounted pawl 46, said pawl being adapted to be maintained in locked position by means of a cam 47, said pawl and cam 47 being mounted upon lugs 48—48, Fig. 110 2, formed integrally with the bearing 43 and overlying said members is a tie-plate 49.

The toothed element 45 includes a circular bearing portion 50 rigidly united with the shaft M and adjacent said portion is a substantially vertically disposed wall portion 51 having adjacent the outer edge thereof a plurality of teeth 52, 53 and 54. Outstanding from said wall portion 51 is an open-ended pocket 55 having a rear wall portion 56 and an upper concave wall section 57 and a lower convex wall section 58, said walls 56, 57 and 58 cooperating to maintain the end of a removable bar 71 adjacent the axial center of the shaft. Disposed at an appreciable distance from said pocket and approximately midway between the walls 57 and 58 is a lateral projection 59, which extends outwardly beyond the end of the pocket walls for the purpose of presenting a 120 125 130

fulcrum to prevent rotation of the removable bar 71 relatively to the pocket. Each of the respective walls 57 and 58 gradually recede in depth towards its outer end to provide a beveled edged surface as indicated at 60 and 61 for the purpose of moving the bar 71 outwardly sidewise on rotation of the shaft at a greater speed than actuation of the bar in a manner more fully described hereinafter.

The pawl 46 is limited in its movement in a locking direction by an abutment portion 62 formed integrally with the bearing bracket member 43, said pawl member being also formed with a weighted portion 63, Fig. 2, which forms a convenient handle for displacing the cam 47 from its locked position. The portion 63 is provided with a recess 64 adapted to cooperate with a tooth-like projection 65, the latter being formed on the cam 47 for the purpose of interengaging with recess 64 on the pawl and thereby maintaining the pawl in an inoperative position with respect to the toothed member 45. The cam 47 is also provided with a lateral projection 66 adapted to engage an edge of the tie-plate when the said cam 47 is moved to an overbalanced position.

The spacing of the teeth 53 and 54 is such as to provide for adjustably controlling and maintaining the door in a primary open position and a secondary open position whereby gradual control of the discharged material may be effected. The arrangement of the teeth provides for a large angular displacement indicated at 67 of the shaft during the opening of the door to the primary position, the position of the mechanism parts and door when opened being indicated diagrammatically at 68, Fig. 2. The angular displacement of the shaft during movement from the primary to the secondary position is considerably reduced as indicated at 69, Fig. 3, although the door moves a greater degree during opening from the primary to the secondary position. The door and mechanism in the secondary position is indicated by dotted lines 70, Fig. 3. The wide angular movement through which the shaft moves during opening movement of the door from the finally closed to the primary open position is of advantage to the operator inasmuch as a certain amount of lifting effort is necessary to displace the mechanism from the tight center locked position.

The operation of the structure is as follows: Assuming the mechanism to be in locked position as shown in Fig. 2, the operator first disengages the pawl 46, then inserts the removable bar 71, Fig. 2. The end of the bar rests on the pocket 55 and bears on the outstanding projection 59. By rotating the bar in a clockwise direction, as indicated at 72, the bar is gripped between the convex wall 58 and the projection 59 and the shaft and bar then rotate in unison until such time as the

dead center connection of the door mechanism is unlocked, whereupon the weight of the load on the doors will cause the latter to open and rotate the shaft at a greater speed than rotated by the bar, a condition commonly known as "overrunning". Due to the fact that the concave wall 58 will move away from the bar and the convex surface 58 will move the bar outwardly, the bar will be automatically disengaged as the shaft overruns. Further, the beveled or wedge shaped formation 61 of the wall will operate to kick the bar sideways outwardly, thus assuring a double factor of safety to the operator. To close the doors, the operator reverses the operation, inserting the bar 71 on the opposite side of the projection 59 in the manner indicated in dotted lines in Fig. 6. The bar is gripped between said wall 57 and the projection 59, and by rotating the bar in an anti-clockwise direction the door will be moved to fully closed position, the pawl 46 cooperating with the toothed element 45 during such rotation of the shaft.

In the construction shown in Figs. 8 to 10, inclusive, the door beam is modified to include integral attaching means adapted to receive a removable diverting member. In said construction the hopper is indicated by inner and outer side walls 200 and 201, and a transversely extending bottom sheet 203. The dumping doors are indicated at 204 and the door brace at 205. The brace is provided adjacent each rail with a plurality of integral brackets 206 each including spaced walls 207, said walls depending from the underside of the beam. Pivotedly mounted at 208 between each pair of walls is a link 209 and disposed on the hopper sheets 203 in alignment with said brackets 207 are brackets 210 each having links 211 mounted thereon. The links 209 on the door and links 211 on the car structure are disposed in aligned relation, and mounted upon said links and depending therefrom are baffle plates 212, the said baffle plates extending above each of the rails 213 for the purpose of dividing the discharging loads to the opposite sides of the rails and maintain the rails free of the discharged load.

When the cars are used for ballasting, these plates and links are applied and may be conveniently removed when the car is returned to normal revenue services.

In the modified construction shown in Figs. 11 and 12, each car hopper is defined by inner and outer side walls as indicated at 300 and 301, respectively, and a transversely extending hopper floor sheet at 302. The inner hopper sheet 300 is flanged outwardly and thence downwardly as indicated at 304 and 305 to provide suitable abutment and sealing means for the door when in closed position. Each door 306 includes a body section 307 and inner and outer marginal flanges 308 and 309, respectively, and a flange adjacent the free

edge of the door 310. The bottom beam in this modification preferably consists of a commercial bar section 311 having the upper flange 312 extending from one door to the other in one plane, the inner flange of the door and the inner hopper sheet being flared as indicated at 313 and 314, respectively, at the intersection with the beam. The upper flange of the channel section 312 is cut away 10 intermediate the doors for the purpose of accommodating a door mechanism eyebolt 315, the said eyebolt being provided with an elongated threaded shank 316, the axis of which extends at an angle to the outstanding web 15 portion of the channel for the purpose of providing a more direct pull on the eyebolt when the door is in closed position. Said eyebolt is retained in position by a nut 317 adapted to be maintained in position by a bracket 20 member 318, said bracket being provided with wall portions 319 and 320, respectively, secured to the upper flange and web of the channel, and in order to compensate for the cut-away portion of the upper flange said member 25 is extended for an appreciable distance to either side of the cut-away portion and secured to the web and flange as indicated at 321 and 322, respectively.

While I have herein shown and described 30 what I consider the preferred manner of carrying out my invention the same is merely illustrative, and I contemplate any changes and modifications that may come within the scope of the claims appended hereto.

35 I claim:

1. In a railway car, the combination of a 40 dumping door, a door brace extending outwardly beyond a side edge of the door and including therein a socket adapted to receive a threaded member, said socket having intermediate its ends a pocket adapted to receive a nut for cooperation with the threaded member, said pocket being adapted to hold the nut against lengthwise and rotary movement; a door operating member rotatably mounted beyond the door; and a link connection between the shaft and the threaded member, said threaded member and link being adapted when the door is in closed position to exert a substantially straight line pull on the nut.

2. In a railway car, the combination of a 55 dumping door, an operating shaft disposed beyond the door, a flanged beam member secured to the underside of the door by one of its flanges and having a web extending at an angle to the main plane of the door, a bracket secured in the angle defined by said web and its flange and including an elongated opening having provisions intermediate its ends for receiving and maintaining a nut against lengthwise and turning movement, said elongated opening extending at an angle to the web of the beam member, and connecting means from the said nut to the shaft.

3. In a railway car, the combination of a 60 dumping door, a flanged beam member secured to the underside of the door, a rotatable operating member, connecting means extending from said operating member to the door, including an eyebolt having a threaded shank 70 extending through a cut-away portion in the flange of the beam member, and a bracket adapted to receive and adjustably hold the said eyebolt in a tilted position with reference to web of the beam member, said bracket being extended to either side of the cut-away portion in the flange and secured on either side thereof to compensate for the cut-away portion.

4. In a railway car, the combination of a 75 dumping door, an operating shaft, connecting means from the shaft to the door, including a member having an elongated shank threaded to accommodate a nut, a flanged beam on the underside of the door having one flange secured to the door and having a web 80 outstanding therefrom at substantially right angles to the plane of the door, a bracket carried by the beam, said bracket having an elongated opening adapted to receive the threaded member and dispose the same at an angle to the web of the beam, said elongated opening having intermediate its ends an open-ended recess adapted to receive the nut and maintain the same against lengthwise and rotary movement.

5. As an article of manufacture a door 90 brace for a substantially vertically suspended car door, said brace incorporating in an integral unit a flanged section for attachment to the car door, a reinforcing body web section outstanding from said flange section, and integral lug means forming a support for a removable ballast diverting member.

6. As an article of manufacture, an integral cast member adapted to be applied for bridging the space as a beam intermediate a pair of transversely aligned doors spaced from each other, said member including means for cooperation with door operating mechanism, and having formed integrally therewith a plurality of spaced bracket means adapted to provide means for suspending auxiliary load diverting means above the rails.

7. As an article of manufacture, a door 110 brace adapted to extend outwardly beyond an edge of the door and including a socket adapted to receive a threaded connection for cooperation with door retaining means, said socket including a pocket adapted to retain a nut intermediate its end for cooperation with a threaded connection, said pocket being adapted to retain the nut against lengthwise and rotary movement.

8. As an article of manufacture, an integral brace member for car doors, adapted to unite a pair of transversely aligned doors spaced from each other a limited distance, said member being provided at a location intermediate

the pair of doors with an opening adapted to accommodate an elongated door supporting connection having a threaded shank and a co-operating nut, and having a pocket intermediate the end of the opening for accommodating said nut and maintaining the same against lengthwise and turning movement.

9. As an article of manufacture, a reinforcing brace for a railway car door, said brace including a flange portion for attachment to the main body of the door and a body portion outstanding from said flange portion, said body portion being deflected from a normal to the main body of the door, said body portion including an elongated recess adapted to retainingly accommodate a connection member, said recess being also deflected from a normal to the main body of the door.

10. In a railway car, the combination of an operating shaft adapted to be rotated, and a unitary element fixedly mounted on the end of the shaft, said element being formed with abutments adapted to receive and retain a removable bar for rotating the shaft in opposite directions, said abutments being so shaped as to release the bar when the shaft is rotated in one direction at a greater speed than that at which it is rotated by the bar.

11. In a door operating mechanism, the combination of a rotatable operating shaft, an open-ended pocket fixed relatively thereto for the purpose of retaining the end of a removable operating bar at a point adjacent the axis of the shaft, and a projection arranged to act upon said bar at an appreciable distance from the axis of rotation of the shaft, the walls of said pocket being so arranged that upon overrunning of the shaft 40 the bar will be thrown both outwardly and sidewise clear of the pocket walls.

12. In a shaft rotating means, an element fixed rigidly to the shaft, said element including two abutments disposed in spaced relation, one of said abutments being located adjacent the axis of the shaft and the other of said abutments being spaced outwardly from the axis beyond the first named abutment whereby a removable bar will be gripped 50 between the respective abutments when the bar is actuated in one direction, said first named abutment comprising an open-ended pocket having associated therewith means for disengaging the bar and shifting it laterally during the same direction of movement of the shaft when the shaft is rotated at a greater speed than that at which it is rotated by the bar.

13. In a railway car, the combination of 60 an operating shaft adapted to be rotated, an element fixedly mounted on the end of the shaft, said element including a weblike depending portion having an open-ended pocket extending laterally from said web, said pocket 65 presenting a flared opening and including

on one side a substantially flat portion and on the opposite side a convex face, said pocket being adapted to engage with and maintain the end of a removable bar adjacent the axial center of the shaft; and a laterally extending projection disposed an appreciable distance from the axis of the shaft and adapted to act upon the bar to prevent turning movement of the same relatively to the pocket, said concave wall of the pocket gradually increasing in depth for the purpose of throwing the removable bar outwardly beyond the pocket when the shaft rotates relatively to the bar at a greater speed.

14. In a railway car, the combination of a dumping door, an operating shaft, a connection extending between said shaft and door to provide a dead center closed toggle effect when the door is in closed position and means for maintaining the door in a plurality of adjusted positions including a primary opening movement of relatively small proportions and a secondary opening movement of relatively greater extent, the arrangement of teeth providing for a large angular movement of the shaft during the primary opening movement and for a relatively smaller angular displacement of the shaft during the secondary opening movement.

15. In a railway car, the combination of a dumping door, door operating means including a rotatable member and connecting means from said member to the door, means for controlling the movement of the door including a toothed element rigid with respect to the rotatable element and a pivoted pawl cooperating with said teeth, said element including a tooth adapted to maintain the door in fully closed position and other teeth adapted to respectively maintain the door in primary and secondary open positions, the tooth arrangement controlling the openings providing for a relatively wide angular movement of the shaft during displacement of the door from the normal closed position to the primary open position and a relatively smaller angular movement during movement of the door from the primary open position to the secondary open position.

16. In a railway car, the combination of a dumping door, an operating mechanism including an operating shaft and connecting means from the shaft to the door, said mechanism including a rigid link member adapted to provide a dead center locking connection, when the door is in closed position, means for graduating the extent of door opening and maintaining the same in a plurality of positions, said means including a toothed element rigid with the shaft and a pivoted locking pawl cooperating with said teeth, said means being adapted to maintain the door in closed position and in a primary open position providing for a smaller degree of opening and in the secondary open position.

tion providing for a relatively greater degree of door movement, the toothed arrangement controlling the primary opening providing for a relatively large angular movement of the shaft during displacement of the door from the normally closed position to the primary opened position and having relatively smaller angular movement of the shaft during movement of the door from the primary opened position to the secondary opened position.

17. In a railway car, the combination of a dumping door, an operating shaft, a connection between the shaft and door, a toothed member carried by the shaft, a bracket on the car structure adjacent an end of the shaft, a weighted pawl carried by the bracket, said pawl having a portion adapted to interlock with the toothed member to maintain the mechanism in adjusted position, and a stop on the bracket adapted to limit movement of the pawl in the locking direction.
